UNITED STATES PATENT OFFICE.

BARBARA C. SMITH, OF ALLIANCE, NEBRASKA.

CORSET MEASURER.

1,407,228.

Specification of Letters Patent. Patented Feb. 21, 1922.

Application filed November 6, 1920. Serial No. 422,328.

To all whom it may concern:

Be it known that I, BARBARA C. SMITH, a citizen of the United States, residing at Alliance, in the county of Box Butte and State 5 of Nebraska, have invented certain new and useful improvements in Corset Measurers, of which the following is a specification, reference being had to the accompanying drawings.

10 The purpose of the present invention is to provide an improved measuring device especially adapted for use by corsetières, for measuring customers, for determining the size of corsets to be manufactured and purchased, although approximate measurements 15 may be taken, in order to determine the size of corsets to be purchased from the stock on hand.

Another purpose is to provide a measurer 20 comprising a bust and back measuring tape, a waist measuring tape and a hip measuring tape having detachable snap fastener connections with tapes including the stays therein, extending along the back, sides and hips 25 and in front, from the bust to the groins, so that when the various tapes are detachably fastened according to the contour or shape of the body, the various measurements for the size of the corset needed may be ascertained.

It is to be noted that the drawing accompanying this specification is more or less 30 illustrative, of the general construction and arrangement of the parts, and is not to be strictly followed, as to the various dimensions or proportions of the tapes of the bust, waist and hip line tapes and the stay tapes, for it is obvious that these parts may be of any suitable or requisite lengths.

40 Still another purpose is the provision of means for fastening the bust, waist and hip line tapes around the body, while the other stay tapes are being applied in position, for the purpose of taking the various measurements.

While the design and construction at present illustrated and set forth is deemed preferable, it is obvious that as a result of a reduction of the invention to a more practical form 50 for commercial purposes, the invention may be susceptible of changes, and the right to these changes is claimed, provided they are comprehended within the scope of what is claimed.

55 The invention comprises further features and combination of parts, as will be herein-

after set forth, shown in the drawings and claimed.

In the drawings:

Figure 1 is a perspective view showing the 60 application of the measurer, the same being constructed in accordance with the invention.

Figure 2 is a perspective view also showing 65 the application of the measurer, but showing the back portion thereof.

Figure 3 is a plan view of the measurer, showing the bust, waist and hip line measuring tapes, and the stay tapes connected thereto.

70 Figure 4 is an enlarged detail view of the connection between one of the stay tapes and the bust tape, showing the two tapes connected detachably.

Figure 5 is a detail view of the modified 75 form of said connection.

Fig. 6 is a sectional view taken on the line 6-6, Fig. 5.

Referring more especially to the drawings, 1, 2 and 3 designate bust, waist and hip line 80 measuring tapes, which may be any suitable length, and are provided with graduations in inches, as indicated at 4. Each of these tapes has its ends connected by means of a suitable fastener 5, such as a buckle or snap 85 fastener. Each of the tapes 1, 2 and 3 is provided with snap fasteners 6, arranged at spaced intervals, for instance an inch apart, though it is obvious that the fasteners may be located at intervals closer or farther apart. 90 These fasteners of the bust, waist and hip line measuring tapes may be either the male or female members, preferably the latter, in order to facilitate the arrangement of the stay tapes.

95 The stay tapes 7 are designed to be disposed in front, from the bust to the groins, and on the sides from the arm pits to and over the waist, and overlie the hips, and also in the back, substantially from adjacent the shoulder 100 blades, down and partially over the buttocks. Furthermore the various stay tapes 7 may be of different lengths, for it is obvious that the invention is not to be limited to any particular length of tape. The stay tapes 7 each 105 comprises closely woven fabric material of any suitable kind, and each of said stay tapes have opposite walls of fabric stitched together as indicated at 9, with stays 10 intermediate the fabric walls or sides of said 110 tapes. These stays may be constructed of any suitable material, such as bone, steel,

- celluloid or the like, in fact any material which is pliable and capable of conforming to the contour of the body, and yet relatively stiff enough so that their positions adjacent to the body may be maintained, while the various measurements are being taken. It is obvious that the stays within the stay tapes may or may not extend the full length of such tape so that a measurer may be used
- 5 for taking measurements for corsets extending down and overlying the hips and of a relatively stiff but pliable character, and whereby a measurer may be afforded for taking measurements for a corset which is
- 10 relatively stiff but pliable a very short distance below the waist line, with the remaining portion of the hip engaging parts of the corset may be relatively flexible and pliable, in fact no stiffening whatever, excepting that
- 15 20 of the fabric material.
- In some corsets the stays extend to the upper edge of the corset, and in others the stays terminate considerably short of the upper edge of the corset, hence it is obvious
- 25 that the stays in the stay tapes may terminate any distance short of the end of the stay tapes, or adjacent the terminals of the stay tapes.
- The stay tapes are also provided with
- 30 35 graduations in inches as indicated at 12, and arranged on the stay tapes are the male members 13 of the snap fasteners, though it is obvious that these male members may be applied to the bust, waist and hip line tapes, and the female members to the stay tapes. The male members 13 of the stay tapes are arranged preferably every half inch apart, though it is obvious that they
- 40 45 may be arranged at other intervals. However, the object in arranging the male members of the fasteners every half inch apart, is to permit a finer adjustment of the stay tapes relatively to the bust, waist and hip line tapes.
- 50 55 In taking a measurement for a pair of corsets, the corsetière first places the bust line tape around the customer, from the bust and closely adjacent the arm pits and the shoulder blades, the customer being obliged to hold the arms up, in order not to interfere with proper measurements. The waist line tape is then applied, likewise the hip line tape. Certain stay tapes are then placed adjacent the side of the
- 60 65 body, from the arm pits to the waist line, and down over the hips. The upper ends of said tapes are connected to the bust line tape by means of the fastener connections, the male member entering the female member. Then the tapes at the sides are fastened to the waist and hip line tapes.

A certain other stay tape herein especially designated by the numeral 14, and corresponding to one of the front steels of the

65 corsets, is then applied to the bust, waist

and hip line tapes, in a manner similar to the application of the side stay tapes. The front stay tape extends from the central portion of the bust downwardly to the waist and overlies the abdomen, as shown

70 clearly in Figure 1. The extreme front stay tape is first connected to the bust tape, and then to the waist line tape, and then finally to the hip line tape.

Certain other stay tapes as shown in Figure 2 are disposed adjacent the small of the back of the body, from a point between the shoulder blades and from under the shoulder blades to the waist line and overlie the buttocks, said tapes being first connected to the top tape, and then the waist line tape and then the hip line tape. The intermediate stay tapes are then fastened in a like manner. After the measurer has been thus applied, the bust, waist and hip line tapes

75 80 85 may be unfastened, and the measurer removed and then the corsetière may take the various readings from the measurer and construct a pair of corsets accordingly.

In Figure 5 the ends of the stay tapes

90 are provided with loops 16 through which the bust line tape extends, therefore, it is obvious that the stay tapes may be carried by the bust line tape, and at the same time be connected thereto by the fastener. It is

95 100 105 obvious that the stay tapes may be connected to the waist and hip line tapes in a similar manner, though it is not illustrated. In case the construction of this kind is used, the loop will be constructed long enough, to

110 permit the waist and hip line tapes to be adjusted in approximately vertical directions.

While it is herein stated that the stays in the stay tapes may be any dimensions, it has been found preferable to use a 19 inch stay in the stay tape at the center of the back and a 19 inch stay in the stay tapes immediately below the shoulder blades. Also it has been found preferable to use 11

115 120 125 inch stays in the stay tapes under the arms, while the stay tapes directly in the front and from the bust to the groin may have stays preferably measuring 12 inches.

The invention having been set forth, what is claimed as being useful is:

1. In a corsetière's measuring device, bust, waist, and hip line measuring tapes having fastener members at spaced intervals thereon, means connecting the ends of each of said tapes when in surrounding relation to the body to be measured, and vertically disposed front measuring tapes having fasteners cooperating with the fasteners of the bust, waist, and hip line tapes and adapted to extend from a point substantially between the breast and terminate adjacent the thighs, vertically arranged tapes connected to the bust, waist and hip line tapes adjustably and extending from points over the
- 130

breast down to and terminating below the outer portions of the thighs, measuring tapes having fasteners cooperating with the fasteners of the bust, waist and hip line tapes 5 and adapted to extend from the arm pits and over the hips and terminate a substantial distance below the hips, and additional tapes having fasteners cooperating with the fasteners of the bust, waist and hip line 10 tapes and adapted to be disposed vertically on the sides of the back and to extend from the upper part of the back down to and over the rumps of the body to be measured, whereby the body may be measured for corsets to extend a substantial distance over 15 the hips, thighs and rumps, the upper end portions of the vertically disposed measuring tapes having elongated loops through which said bust line measuring tape loosely 20 passes, whereby the bust line measuring tape may be fastened around the body over the bust for adjustably suspending the vertical measuring tapes.

2. In a corsetière's measuring device, bust, 25 waist, and hip line measuring tapes having fastener members at spaced intervals thereon, means connecting the ends of each of said tapes when in surrounding relation to the body to be measured, and vertically disposed front measuring tapes having fasteners cooperating with the fasteners of the bust, waist and hip line tapes and adapted

to extend from a point substantially between the breast and terminate adjacent the thighs, vertically arranged tapes connected 35 to the bust, waist and hip line tapes adjustably and extending from points over the breast down to and terminating below the outer portions of the thighs, measuring tapes having fasteners cooperating with the 40 fasteners of the bust, waist and hip line tapes and adapted to extend from the arm pits and over the hips and terminate a substantial distance below the hips, and additional tapes having fasteners cooperating 45 with the fasteners of the bust, waist and hip line tapes and adapted to be disposed vertically on the sides of the back and to extend from the upper part of the back down to and over the rumps of the body to be measured, whereby the body may be measured for corsets to extend a substantial distance over 50 the hips, thighs and rumps, said vertically disposed measuring tapes having elongated loops approximating positions adjacent the 55 bust, waist and hips, for the reception of the bust, waist and hip line measuring tapes, whereby the latter tapes may be easily adjusted relative to the vertical tapes and vice versa, without entirely detaching the tapes. 60

In testimony whereof I hereunto affix my signature.

BARBARA C. SMITH.
